(57) **CLAIM**

The ornamental design of an audio player apparatus, as shown and described.

DESCRIPTION

FIG. 1 comprises a top, front perspective view of the audio player apparatus according to the present invention; FIG. 2 comprises a rear perspective view of the audio player apparatus;

FIG. 3 is a front view of the audio player apparatus;

FIG. 4 is a back view of the audio player apparatus;

FIG. 5 is a top view of the audio player apparatus;

FIG. 6 is a bottom view of the audio player apparatus;

FIG. 7 is a left side view of the audio player apparatus;

FIG. 8 is a right side view of the audio player apparatus;

FIG. 9 is a rear view of the audio player apparatus with the detachable pack removed, shown separately for clarity of illustration;

FIG. 10 is a top perspective view of the detachable pack for the audio player apparatus, shown separately for clarity of illustration; and,

FIG. 11 is a bottom perspective view of FIG. 10.
